UNITED STATES PATENT OFFICE.

ALONZO LINTON BAUSMAN, OF SPRINGFIELD, MASSACHUSETTS, ASSIGNOR TO NATIONAL EQUIPMENT COMPANY, OF SPRINGFIELD, MASSACHUSETTS, A CORPORATION OF MASSACHUSETTS.

CONFECTION-COATING MACHINE.

Application filed November 10, 1924. Serial No. 748,931.

This invention relates to improvements in confection coating machines and, more particularly, to that type of machine wherein the confections are carried through a casing by a conveyer and coated by traveling through a stream of coating material.

In machines of this general type, various working parts become covered with the coating material, usually chocolate, and are hard to clean. It is difficult to keep the machine in that clean, sanitary condition which is to be desired, considering that the products of the machine are intended for human consumption. While the machines can be, and should be frequently cleaned, they are so constructed that the cleaning operation is rather hard to perform and accordingly, it is often neglected.

This invention is concerned with, and has for its general object, the provision of a confection coating machine, wherein all of the essential working parts, which are subjected to the coating, can be quickly and conveniently removed from the casing, and easily cleaned as separate units under the most favorable conditions, leaving the casing entirely free of the usual obstructions so that an operator can easily enter the casing and clean the same and other stationary parts affixed thereto.

While certain of the working parts of a confection coating machine, such as the chocolate supply tank and the screw elevating means therefor, have heretofore been made removable, I wish to point out that the problem is only partially solved thereby. The supply tank and the screw elevator may, it is true, be as readily cleaned as with the present invention, but their removability does not contribute to the desired result of facilitating the cleaning of the machine, as a whole. The chief difficulty with prior machines has been that the pervious conveyer, or so called "wire belt", together with its various supports and driving and guiding rolls, has not been removable and these elements, in effect, partition the casing into two parts, each of which is too small to allow convenient access to the interior of the casing for the cleaning operation. The removal of the wire belt, and its associated elements, is, therefore, the keynote to the successful accomplishment of the desired object because the principal obstruc-

tion to free access into the casing is removed and also because the belt and its associated elements are exceedingly difficult to properly clean while held in place in the machine.

Other objects and advantages will appear in the following description and in the illustrative embodiment of the invention, in the accompanying drawings, in which:

Fig. 1 is a small scale front elevational view with parts broken away, of a confection coating machine embodying the invention;

Fig. 2 is an end elevational view, taken on the line 2—2 of Fig. 1, with the doors, which normally close this end, removed to show the interior construction;

Fig. 3 is a sectional plan view taken on the line 3—3 of Fig. 1;

Figs. 4 and 5 are fragmentary, sectional elevational views, taken on the lines 4—4 and 5—5, respectively, of Fig. 3;

Fig. 6 is a plan view of the machine, showing the driving mechanism;

Figs. 7 and 8 are fragmentary sectional views taken on the lines 7—7 and 8—8, respectively, of Fig. 6 and also illustrative of the driving mechanism;

Fig. 9 is an enlarged fragmentary sectional elevational view taken on the line 9—9 of Fig. 3; and

Fig. 10 is a fragmentary cross-sectional view taken on the line 10—10 of Fig. 3.

Referring to these drawings and particularly to Fig. 1; the machine, in its fundamentals, is similar to that disclosed in U. S. Letters Patent No. 735,890, granted August 11, 1903, on an invention of E. P. F. Magneiz. It includes a suitably heated casing A, through which the confections to be coated are carried by a pervious conveyer b, usually of wire mesh construction. Confections are supplied to the wire belt b by a feed belt c and the coated confections are transferred from belt b to a delivery belt d. The coating material is contained within a main supply tank e, housed within casing A below belt b and mounted on a wheeled truck f, whereby it may be rolled into or out of casing A through a door A', after the general manner disclosed in said patent. Coating from tank e is carried upwardly through a tube g (Fig. 2) by an elevating screw h and delivered by way of a spout i into a shower pan j, from which it issues through a slot k (Fig. 1) in

a downwardly directed stream upon the confections carried by belt *b*. A pair of rolls *l*, mounted directly below belt *b*, pick up some of the coating passing therethrough and apply it to the bottoms of the confections in the usual manner. The confections, thus coated, are carried by belt *b* in under a fan *m*, from which a downwardly directed blast of air issues upon the confections to remove superfluous coating. Any wrinkles in the coating, due to the action of the fan, are smoothed out by vibrating belt *b* in the usual manner by means later to be described.

The wire belt *b* is of usual and well known construction and travels, in its upper stretch, horizontally from one end of casing *A* to and beyond the other end and into an extension. This extension comprises side frames *n* and inner and outer bottom walls *o* and *o'* (Figs. 4 and 5). The frames *n* are connected to casing *A* at one end and supported at the other end by legs *p*. At the ends of the upper stretch of belt *b* are very small rolls *q* and *r* and the lower stretch is guided around rolls *s* and *t*, the former being a tension roll and the latter the driving roll. Intermediate the rolls *q* and *r*, are grid like frames *u*, *v* and *w* which function to support belt *b* in its upper stretch of travel and may also act to vibrate it, as and if desired. As shown, frames *v* and *w* are vibrated while frame *u* is not.

The frames *u*, *v* and *w* are each of similar construction and a description of one will suffice for all. These frames are best shown in Figs. 3, 4 and 10 and each comprises two laterally spaced side bars *15* connected together by two cross bars *16* to which are fixed in laterally spaced relation a plurality of longitudinal bars *17* set on edge. The upper faces of the bars *15* and *17* are arranged to contact with belt *b*. Each side bar *15* is forked at one end to straddle a stud *18* mounted in the adjacent side frame *n*, whereby each frame is pivotally supported at one end on a pair of these studs and may be lifted free therefrom and removed, when desired. The studs of each pair are shouldered, as shown in Fig. 3, to hold the frame from side-wise movement. The pivot studs *18* for frame *w* are fixed in frames *n* but the other studs extend through and beyond the frames and have fixed on their outer ends ratchet wheels *19* and outside these wheels sprockets *20*. The forward ends of the side bars *15* of frames *v* and *w* are offset outwardly and upwardly to overlie the ratchet wheels *19* and carry vertically adjustable pawls *21*, to operate therewith. The forward ends of the side bars of frame *u*, which is not vibrated, rest on shouldered down portions of the nearest bottom coating roll *l*, as clearly shown in Figs. 3 and 4. It will be seen that each of the frames *u*, *v* and *w* is conveniently removable, when the tension of belt *b* is re-

laxed by simply lifting them free of the ratchets *19* and studs *18*. Thus, all the intermediate supports for belt *b* are mounted for convenient and expeditious removal.

The various rolls which engage belt *b*, are likewise mounted for quick and convenient removal. These rolls are naturally arranged in two groups, one at each end of belt *b*, and, by preference, are removable from the machine in groups rather than individually, as by so doing the dismantling of the necessary parts for cleaning is so much the more quickly performed. It is recognized, however, that the particular groups chosen may be subdivided and other groups formed and that rolls may even be removable individually. In the present case, rolls *l*, *q* and *s* constitute one group and rolls *r* and *t* the other group.

Referring to Figs. 2, 3, 4 and 5, the rolls *l*, *q* and *s* of the first named group are rotatably mounted at their ends in, and extend between, a pair of laterally spaced, parallel side frames *22* arranged one adjacent each side of casing *A*. Each frame *22* has an outwardly extending horizontally disposed flange *23* which rests upon a horizontally arranged angle iron *24* fixed by brackets *25* to the side walls of casing *A*. A pair of longitudinally spaced pins *26* are fixed in upstanding relation on each angle iron *24* and each flange *23* fits between a pair of the pins *26* and is held from endwise movement thereby. One face of each frame *22* abuts the inner face of the angle irons *24*, whereby the frames are held from moving outwardly, and inward movement of the frames is prevented by the rolls therebetween, which are shouldered near their ends to abut the inner faces of the frames. It will be evident that frames *22*, with the rolls *l*, *q*, and *s*, may be removed as a unit by simply lifting them free of the angle irons *24* and pins *26*. These frames, when removed, may be held from separating in any suitable manner and, as shown, may be held sufficiently by the gears *27* and *28*, fixed to opposite ends of one roll *l*, outside frames *22*. The gear *28* drives by an idler gear *29* a gear *30* on the other roll *l*. The rolls *q* and *s* are not driven. Roll *q* is provided with the customary scraper *31* and roll *s* is mounted for longitudinal adjustment and is forced to the left (as viewed in Fig. 4) by springs *32*, which thus serve to tension belt *b*.

Referring to Figs. 3, 4 and 5, the second group of rolls, comprising rolls *r* and *t*, are mounted at their ends in, and extend between, two spaced side frames *33*, which are removably mounted at the outer ends of frames *n*. These frames are cut out in step fashion and the frames *33* are correspondingly formed to fit in the cut out portions. They are held in place by spring pressed pins *34* (see Fig. 9) which are slidably

mounted in frames 33 and enter into holes in frames *n* to hold frames 33 against upward or sidewise displacement,—longitudinal displacement being prevented by the tension of belt *b* which holds frames 33 snugly against frames *n*. The roll *r* has fixed to its rear end a pinion 35 which is driven through an idler 36 from a gear 37 fixed on the rear end of a shaft 38. The latter is 10 rotatably mounted in frames 33 and at its forward end carries a gear 39 which is driven by a gear 40 rotatably mounted on the front frame *n* adjacent to frame 33. Fixed to gear 40 is a gear 41 which drives 15 a gear 42 fixed on roll *t*. The gears 37 and 39 prevent separation of frames 33, when removed, and the roll *t*, being shouldered near its ends, prevents inward movement of the frames. The latter may be easily removed 20 by pulling outwardly on pins 34 and then lifting the frames 33 above frames *n* and pushing them inwardly (to the left) until belt *b* is loosened sufficiently to allow the frames 33, and associated parts, to be 25 removed from the loop of the belt.

The various moving parts, associated with the wire belt *b*, are all driven from a shaft 43 which extends from the driving mechanism, (mounted on a bed 44 at the upper 30 part of casing A, Fig. 7), vertically downward near the front wall of the casing and carries at its lower end a bevel gear 45 (Figs. 3 and 10). Meshing with the latter is a bevel gear 46 fixed near one end, to a shaft 35 47 which extends horizontally across the casing and carries two sprockets 48, one on each side of belt *b* (Fig. 10). Each sprocket 48 is connected by a chain 49 (Fig. 5) to other sprockets fixed to the ratchet 30 wheels 19, whereby the rapping frames *v* and *w* are operated, and one chain 49 also extends to and drives a sprocket 50 rotatably mounted near the outer end of the front frame *n*. Sprocket 50 is fixed to a gear 51 which drives the gear 40, heretofore described, and thus the rolls *r* and *t*. Fixed to shaft 47 is a gear 52 (Figs. 3 and 5) which drives by idler intermediate gears 53 a gear 54 on a horizontal shaft 55. Shaft 55 is mounted at one end in the front wall of casing A and at the other end in a bracket 56 and carries at its inner end a gear 57 to drive the described gear 27 and thus both rolls *l*.

The wire belt drive shaft 43 extends above bed 44 and is connected by bevel gears 58 (Figs. 6 and 7) to a horizontal shaft 59, which has fixed thereon a series of gears 60, of graded sizes. Parallel with shaft 59 is a shaft 61 on which is slidably keyed a group of gears 62, one to correspond with each gear 60. The arrangement is such that any one of the gears 62 may be moved to mesh with one of gears 60 whereby a selective change 60 speed transmission from shaft 61 to shaft 59

is obtained and whereby the speed of the wire belt may be varied, as desired. A yoke 63, forked at one end to straddle gears 62, is threaded at its other end on a rod 64, rotatably mounted at its ends in the front and 70 back walls of casing A and provided with a hand wheel 65, outside the casing, whereby it may be turned. Shaft 61 is driven by spur gears 66 from a shaft 67 mounted directly thereabove and shaft 67 is driven by 75 a belt 68 and suitable pulleys from an electric motor 69 mounted on bed 44.

The feed and delivery belts *c* and *d* are driven from shaft 59 through a selective gear transmission, whereby their speeds may be 80 changed relatively to that of the wire belt *b*. Referring to Fig. 8, a short shaft 70 is mounted directly below shaft 59 and has fixed thereto a series of gears 71 of graded sizes. A corresponding group of gears 72 are provided on shaft 59. The corresponding gears of each group are always in mesh but only one of the gears 72 at a time can be keyed to shaft 59. The latter is grooved to receive a sliding key 73 which can be moved 85 axially and engaged with any one of gears 72. The key 73 is carried by a grooved collar 74 with which a shifter fork 75 is engaged. Fork 75 is threaded on a rod 76, mounted similarly to rod 64 and provided, 90 outside casing A, with a hand wheel 77, whereby it may be turned to effect speed changes between shafts 59 and 70. The latter carries a sprocket 78 which is connected by a chain 79 with a sprocket 80, rotatably mounted on a stud on the rear wall of casing A below belt *b*. Fixed to sprocket 80 is a bevel gear 81 which meshes with a bevel gear on a horizontal shaft 82 disposed longitudinally of casing A and behind and below 95 belt *b*. The ends of this shaft are provided with universal joint connections 83 and 84 to receive corresponding connections on the drive shafts for the feed and delivery belts respectively.

The drive for each belt is similar and a description of that for the feed belt will suffice for both. Referring to Fig. 1, a shaft 85 is connected at one end to the universal joint 83 and at the opposite end to a similar joint 86 which connects with a short shaft 87 mounted in brackets on a pedestal 88. The latter rotatably supports the drive roll 89 for belt *c* and the drive roll carries a worm wheel 90 driven by a worm 91 on a shaft 92, mounted on pedestal 88 above shaft 87 and driven therefrom by spur gears 93. Shaft 85 is usually covered by a tube 94 on the ends of which are open ended cups 95 and 96 to encompass the universal joint connections 83 and 86, respectively. This tube, and the shaft therein, need to be removed for convenience in withdrawing the tank *e* through door A'. The cup 95 is held to its tube by a set screw 97 and, when this screw 100

is loosened, the cup may be slid back on the tube far enough to expose shaft 85. The latter is held to joint 83 by a set screw 98 and, when this screw is loosened, shaft 85 may be 5 pushed to the left into the joint 86, to which it is slidably keyed, far enough to disconnect it from joint 83, whereupon the shaft and tube may be pulled out of line with joint 83 and then to the right to disconnect it 10 from joint 86.

The feed belt *c* is trained over a table comprising two sections 99 and 100, arranged end to end and hinged together at 101. The section 99 is pivotally connected 15 at 102 to pedestal 88 and the opposite end of section 100 is supported by resting on brackets 103 on casing A. Stops 104 fixed to the sides of section 99 engage lugs 105 projecting outwardly from the lower face of section 20 100 and prevent the sections from downward jackknife movement and normally hold the sections in a common horizontal plane to support the feed belt in its upper stretch of travel. The sections, however, may be moved 25 upwardly in jackknife fashion into the position shown by dotted lines in Fig. 1 and, when so moved, may be held in this position by brackets 106 on pedestal 88 which support the lower end of section 100. This operation 30 can be quickly and conveniently performed without removing belt *c*, and as a result, the space between pedestal 88 and casing A is cleared to facilitate the operation of withdrawing tank *e*.

The tank *e* is jacketed, as shown in Fig. 2, and is provided with a suitable stirrer, such as 108, which is fixed to the upper end of a centrally and vertically disposed shaft 109, which extends downwardly through a long 40 hub 110 in tank *e*, and through the floor of truck *f*, and carries at its lower end a bevel gear 111. In mesh with the latter is a bevel pinion 112 fixed on one end of a short shaft 113, mounted beneath the floor of truck *f* 45 (Fig. 1). The rear wheels of the truck closely fit between tracks 114 on the bottom of casing A and stops 115 extend upwardly behind these wheels to arrest the same in proper position. When the truck is thus 50 positioned, a clutch jaw 116 on shaft 113 is aligned with a mating jaw 117 fixed on one end of a shaft 118 slidably mounted in one end of casing A and adapted to be moved endwise by a shift lever 119 to carry jaw 55 117 into engagement with jaw 116. Slidably keyed to shaft 118 is a sprocket 120 which is connected by a chain 121 to a sprocket 122, fixed on the described shaft 82, outside casing A, whereby the stirrer 108 is driven.

The bottom of tank *e* is connected, at one side, by a passage 123 (Fig. 2) to a vertically disposed cylindrical well 124, which loosely receives the lower end of the screw elevator tube *g*. Fixed to the lower end of

the latter is a fork shaped bracket 125 which receives, and forms a step bearing for, the lower end of the elevating screw *h*. The lower end of bracket 125, by abutment with the bottom of well 124, positions the tube *g* vertically. This tube is held from lateral displacement by a two part encompassing clamp, comprising a section 126 fixed to a side wall of casing A and a section 127 pivoted to section 126 at one end and adapted to be held thereto at the other end by a 75 clamping screw 128, all as shown in Fig. 3. By releasing screw 128, and swinging section 127 outwardly, the tube *g*, while still in place in well 124, may be withdrawn from casing A when tank *e* is withdrawn, after 80 which tube *g* can be removed by simply lifting it out of well 124.

In order to drive screw *h* in a manner such as to permit it to be quickly and conveniently disconnected for removal, when desired, the following mechanism is employed. The upper end of screw *h* is squared, as at 129, (Fig. 2) to fit in a correspondingly formed socket in a member 130, fixed to the lower end of a short vertical 90 shaft 131. The latter extends through the bed 44 and is slidably keyed to a bevel gear 132. The weight of part 130 normally holds it in engagement with the squared end 129 but it may be disengaged therefrom by lifting shaft 131 until the key 133 is drawn out of gear 132. By then turning shaft 131 far enough to carry key 133 out of alignment with its keyway in gear 132, the part 95 130 is held in raised position so that tube *g* and screw *h* may be withdrawn from casing A. Gear 132 meshes with a bevel gear 134 (Figs. 6 and 7) fixed to one end of a short horizontal shaft 135 mounted in bearings upon bed 44. The other end of shaft 100 135 carries a bevel gear 136 which meshes with a bevel gear 137. The gear 137 is fixed to the hub of a clutch jaw 138 and the latter is loosely mounted on the shaft 61, above 105 described. Slidably keyed to shaft 61 is a mating clutch jaw 139 which is movable by means of a shifter fork 140 into engagement with jaw 138. Fork 140 is fixed to a slidable rod 141 which extends outside casing A and carries an actuating handle 142.

The fan *m* is supported by brackets 143 (Fig. 2) secured to the lower face of bed 44 and disposed one at each end of the fan. On one end of the shaft 144 of the fan is a pulley 145 which is driven by a belt 146 from an electric motor 147 mounted on bed 44.

The shower pan *j* has on each end an outwardly extending flange 148 (Figs. 1 and 2) and is supported by these flanges which rest upon horizontally disposed angle irons 149 which in turn are supported by brackets 150 depending from bed 44. The shower pan is held from endwise displacement on 125

the angle irons 149 by and between pairs of upstanding pans 151 which engage the ends of flanges 148.

The tank *e* may be filled, while in place in casing *A*, by means of a trough 152 (Fig. 2) the mouth of which is disposed outside casing *A* and the exit end of which overlies the top of the tank.

The casing *A* is entirely closed on the front and rear sides. The lower portion of the casing, forming the housing for tank *e* is permanently closed at one end and at the opposite end is closed by door *A'*. Above the belt *b*, suitable doors *x* and *y* are provided to close the end walls of the casing, except for small openings to permit the passage of the confections into and out of the casing.

The operation of the machine, in so far as the coating of confections is concerned, is no different than usual and will sufficiently appear from the foregoing description. The operation of removing the essential working parts of the machine is usually started by lifting the feed table sections 99 and 100 and moving them into their folded positions, illustrated by dotted lines in Fig. 1, which clears the space for the removal of the supply tank *e*. The shaft 85 and its enclosing tube 94 are next uncoupled, as already described. The doors *A'* and *x* are then opened to clear the way for the removal of tank *e* and the screw elevator tube *g*. The shaft 131 is pulled upwardly to disengage the member 130 from the squared end 129 of the screw elevator *h* and is turned to carry its key 133 out of line with the keyway in gear 132, whereby member 30 is held in raised position. The clamping screw 128 is loosened and swung free of clamp 127 and the latter swung outwardly to release tube *g*, whereupon tank *e* with the tube *g* in place in well 124 may be rolled out of casing *A*, the tank being preferably first disconnected from its operating mechanism by operating lever 119 to separate the clutch jaws 115 and 116. The shower pan *j* is then removed through the open door *x* by lifting it free from its angle iron supports 149. The removal of the wire belt and associated parts is started from the delivery end of the machine by removing frames 33. This is effected by first pulling out pins 34 and then raising the frames 33 until they clear the upper edges of frames *n*, after which the frames 33 are moved toward the feed end of the machine until there is slack enough in belt *b* to permit the frames 33, and rolls carried thereby, to be drawn laterally out of the loop of the endless belt *b*. The frames 33, having been removed and the belt *b* left loose and free at one end, the rapping frames *w* and *v*, are successively removed in the order named. In removing these frames, they are simply lifted free of studs 18 and

then withdrawn laterally from the loop of belt *b*. The frame *u* is usually removed from the feed end of the machine after the frames 22, and the rolls carried thereby have been removed. To remove frames 22, they are simply lifted free of their angle iron supports 24, and the pins 26 carried thereby, and then pulled endwise through door *x*. As these frames are pulled out, the rolls *q* and *s* drag belt *b* along with it and after the frames have been entirely withdrawn from casing *A*, they and their rolls may be withdrawn laterally from the loop of belt *b*. With frames 22 removed, access is readily had to frame *u* which is pulled out through door *x* and out of belt *b*, after which the belt itself is completely drawn out.

The operations described are far more easily and quickly accomplished than would appear from the description and a single operator can dismantle the machine, in the manner described, in a very few minutes. With the parts removed as described, an operator can enter casing *A* and clean the sides thereof, the adjacent stationary parts and any other parts which may become covered with chocolate. The cleaning can be easily and thoroughly done because the operator works under favorable conditions and everything is freely accessible for the purpose, after stripping the casing of the main working parts as above described. The parts removed can likewise be cleaned under favorable conditions. The group including frames 22 and the group including frames 33 can be cleaned as a unit without dismantling the individual parts. The elevator mechanism is, however, usually taken apart. For this purpose the screw *g* is lifted out of tube *h* and the tube is then lifted out of well 124.

Aside from the mounting of the wire belt for convenient removal, which is an essential to the results sought to be accomplished, the arrangement for collapsing the feed belt table is thought to be particularly important. It is important, in any event, to give free access to one end of the casing *A* to enable the removal of the wire belt to be the more readily performed, whether or not tank *e* is removable. It is also especially important to the practical and successful use of a removable tank, particularly when there is associated therewith an elevating device which is drawn out with the tank in assembled relation. Such a tank and elevator cannot readily be withdrawn through the front and rear walls of the casing because these walls carry the bearings for a number of moving parts. One end of casing *A* is blocked by the extension frames *n* and, because of this fact and the fact that the elevator is adjacent the feed end of the machine, the removal of the elevator has to be effected from the feed end of the machine. This feed end, however, is blocked by the

feed belt which, except for the collapsible arrangement described, would have to be removed as an entirety, necessitating the unbolting the pedestal 88 and the bodily shifting of a considerable weight.

The parts, removed from casing A as above described, may be reassembled therein by reversing the operations described and performing them in reverse order.

10 The invention has been disclosed herein in an embodiment at present preferred, for illustrative purposes, but the scope of the invention is defined by the appended claims rather than by the foregoing description.

15 What I claim is:

1. In a confection coating machine, a casing, an endless belt for carrying confections therethrough, spaced devices over which said belt is trained in loop form and disposed one at each end of the confection carrying stretch thereof, and means for holding said devices against movement toward one another, said means permitting either device to be lifted therefrom and 25 when so lifted to be moved toward the other device sufficiently to allow it to be slipped endwise out of the loop of said belt leaving the latter free for removal from the casing.

2. In a confection coating machine, a casing, an endless belt for carrying confections therethrough, spaced devices over which said belt is trained in loop form, means for holding said devices against movement toward one another, said means permitting either 35 device to be lifted therefrom and when so lifted to be moved toward the other device sufficiently to allow it to be slipped endwise out of the loop of said belt and intermediate devices for supporting said belt each mounted in said casing so as to be conveniently 40 lifted free and removed endwise from the loop of the belt after one of said first named devices has been removed leaving the latter free for removal from the casing.

45 3. In a confection coating machine, a casing, a conveyer to carry confections through said casing, fixed supports at opposite ends thereof, frames detachably mounted on said supports and end supporting rolls for said 50 conveyer mounted one in each of said frames.

4. In a confection coating machine, a casing, a conveyer to carry confections through said casing, fixed supports at opposite ends thereof, frames detachably supported from 55 said supports and a group of conveyer engaging rolls mounted in each of said frames.

5. In a confection coating machine, a casing, a conveyer to carry confections through said casing, fixed supports at opposite ends 60 thereof, frames detachably supported from said supports, upper and lower rolls for supporting and guiding one end of the conveyer mounted in one of said frames and an upper roll and a lower driving roll mounted

in the other frame for engaging the other 65 end of the conveyer.

6. In a confection coating machine, a casing, a conveyer to carry confections through said casing, fixed supports at opposite ends thereof, frames detachably supported from 70 said supports, a group of conveyer engaging rolls mounted in each of said frames, and a series of supports each removably mounted in said casing intermediate the last named supports for underlying and supporting the 75 upper lap of said conveyer.

7. In a confection coating machine, a casing, a conveyer to carry confections through said casing, fixed supports at opposite ends thereof, frames detachably supported from 80 said supports, upper and lower rolls for supporting and guiding one end of the conveyer mounted in one of said frames, bottom coating rolls also mounted in the last named frame and an upper roll and a lower driving 85 roll mounted in the other frame for engaging the other end of the conveyer.

8. In a confection coating machine, a casing, a conveyer to carry confections through said casing, fixed supports at opposite ends thereof, frames detachably supported from 90 said supports, a group of conveyer engaging rolls mounted in each of said frames, a series of grid like supports each removably mounted in said casing intermediate the last named supports for underlying and supporting the upper lap of said conveyer, and means for vibrating certain of said grid like frames.

9. In a confection coating machine, a pair of laterally spaced side frames including removable sections at opposite ends, a confection carrying conveyer adapted to travel between said frames, rolls for supporting and guiding said conveyer mounted in each of said end sections, a series of pairs of longitudinally spaced and inwardly extending studs mounted in each frame between said end sections, a grid like frame pivotally and detachably mounted at one end on each of said studs and a ratchet wheel revolvably 100 mounted on each of certain of said studs to support the opposite ends of said frames.

10. In a confection coating machine, a casing, an endless conveyer for carrying the confections through the latter, driving, guiding and supporting means therefor mounted in said casing for convenient detachment and arranged when detached to be slipped sideways out of the loop of said endless conveyer leaving the latter free for removal from said 110 casing.

11. The combination with a confectionery coating machine and its confection carrying belt, of a feed table over which confections are fed to said belt, a support for one end 125 of said table at a distance from the machine to which support said end is movably connected, and a support on said machine

upon which the other end of said table normally rests, said table comprising a plurality of sections connected one to the other for relative shifting movement and arranged to be shifted relatively to each other and relatively to the first named support into an inoperative position in which a clear space is left between said supports.

12. A feed table for a confectionery coating machine comprising a plurality of hingedly connected sections, a fixed support spaced from said machine for one end of one of said sections, a fixed support adjacent said machine for the opposite end of another of said sections, one of said sections being pivotally connected to its support, and inter-engaging means on the adjacent ends of adjacent sections to hold them in a common plane and in normal working position, said sections arranged to fold relatively to one another and to swing on said pivotal connection into an inoperative position in which a clear space is left between the supports.

13. The combination with a confection coating machine, of a feed table therefor, comprising two hingedly connected sections normally lying end to end in a common plane, a support spaced from said machine to which support one end of one of said sections is pivotally connected, a support adjacent said machine for the opposite end of the other section, said sections arranged to fold upwardly in jackknife fashion and to swing upwardly on said pivotal connection into an inoperative position, and means on one section to engage the other section and prevent jackknife movement of the sections in a downward direction.

14. The combination with a confection coating machine, of a feed table therefor, comprising two hingedly connected sections normally lying end to end in a common

plane, a support spaced from said machine to which support one end of one of said sections is pivotally connected, a support adjacent said machine for the opposite end of the other section, said sections arranged to fold upwardly in jackknife fashion and to swing upwardly on said pivotal connection into an inoperative position, means on one section to engage the other section and prevent jackknife movement of the sections in a downward direction, and means on the first named support for holding said sections in inoperative position.

15. The combination with a confection coating machine, of a feed table therefor, comprising two hingedly connected sections normally lying end to end in a common plane, a feed belt travelling over said table in its upper lap and returning in its lower lap beneath said table, a support spaced from said machine to which support one end of one of said sections is pivotally connected, a support adjacent said machine for the opposite end of the other section, said sections arranged to fold upwardly in jackknife fashion and to swing upwardly on said pivotal connection without removing said belt into an inoperative position, and means on one section to engage the other section and prevent jackknife movement of the sections in a downward direction.

16. In a confection coating machine, a casing including a pair of laterally spaced fixed supports at one end thereof, a conveyer to carry confections through said casing, a pair of laterally spaced members detachably mounted one on each of said supports, and an end supporting roll for said conveyer mounted near its ends in and extending between said members.

In testimony whereof I have affixed my signature.

ALONZO LINTON BAUSMAN.
